GARMENT

Lily Loscher, New York, N. Y.

Application December 23, 1936, Serial No. 117,253

13 Claims. (Cl. 2-97)

This invention relates to garments, such as coats, jackets, or the like sleeved garments.

An object of this invention is to provide a garment of the character described, having a quickly detachable lining provided with an integral collar.

A further object of this invention is to provide a sleeved garment of the character described, having a lining detachably attached thereto by slider actuated fasteners at the sleeve cuffs and at 10 the front and around the neck line of the garment, the lining having integral portions adapted to be exposed at the cuffs and collar when the lining is worn and having the appearance of being part of the coat.

Another object of this invention is to provide a sleeved garment provided with cuffs on the sleeves, detachable from the sleeves and adapted to be attached at the neck of the garment and together form a collar for said garment.

Yet another object of this invention is to provide an ensemble consisting of a coat, a detachable light lining attachable thereto to match the dress worn under the coat, and having integral trimmings at the neck and cuffs, matching the dress and adapted to be exposed when the lining is used, and a second lining adapted to replace the first lining and made of a heavier or warmer material and provided with an integral collar adapted to fold over the neck portion of the coat; 25 whereby said coat may be worn without either lining, or with the light lining, or with the heavy lining, depending upon the weather or the occasion.

A still further object of this invention is to provide a neat and attractive garment of the character described, which shall be inexpensive to manufacture, which may be executed in many varied attractive designs, and which is yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which are shown one of the various possible illustrative embodiments of this invention,

Fig. 1 is a perspective view of a garment embodying the invention, illustrating the coat with a light lining matching the dress worn beneath the coat;

Fig. 2 is a perspective view of the coat and lining shown in Fig. 1 opened up, with part of the lining partly detached;

Fig. 3 is an enlarged, detailed view showing a portion of the lining and collar trim and part 60 of the coat;

Fig. 4 is a cross-sectional view taken on line 4-4 of Fig. 3;

Fig. 5 is a perspective, detailed, partial view of one corner of the coat and lining, with parts broken away to disclose the slider actuated fastening means;

Fig. 6 is a cross-sectional view taken through the cuff of the coat shown in Fig. 2, with the sleeve lining attached thereto;

Fig. 7 is a perspective view of the coat, provided with a heavy lining having an integral folded-over collar;

Fig. 8 is a perspective view of a portion of the neck of the coat with lining and collar attached thereto, and with parts in cross-section;

Fig. 9 is a perspective view of a jacket embodying the invention, provided with fur cuffs on the sleeves adapted to be detachably attached by slider actuated fasteners and attached to the neck portion to form a collar for the jacket;

Fig. 10 is a cross-sectional view taken through one of the sleeves of the jacket shown in Fig. 9, and its cuff;

Fig. 11 is a plan view of one of the cuffs detached from the garment and stretched out;

Fig. 12 is a front elevational view of the neck portion of the jacket of Fig. 9; and

Fig. 13 is a perspective view of a coat with collar similar to jacket of Fig. 9.

Referring now in detail to the drawing, 10 designates a basic garment or coat on a figure 11 and provided with sleeves 12 and being split down the front. Detachably attached to the inside of the coat is a supplementary garment or lining 15. The lining 15 likewise has sleeve portions 16 disposed within the sleeves 12 of the coat. The sleeve portion 16 is provided with an integral collar trim 17 adapted to be exposed at the neck of the wearer when the lining is worn with the coat. Cuff trims 18 may also be stitched to the 40 ends of the sleeve linings 16, said trims 18 likewise being exposed when the coat and lining are worn. The lining 15 with its sleeves 16 are detachably attached to the coat by slider actuated fastener means 19 extending around the front 45 split edges of the garment as at 20, around the neck of the garment as at 21, below the trim 17, and at the cuffs or ends of the sleeves 12 as at 22 short of the trims 18.

The lining 15 may be made of a light material, such as silk, similar to or matching the material of the dress 25 worn beneath the coat. The bottom edge of the dress may be provided with a trim 26 matching the collar trim 17 and cuff trims 18. When the coat 10 is open somewhat at 55 the front to expose the lining 15, a harmonious effect will be produced because the lining material is the same as or matches the dress material 25 which may be seen at the front where the coat is opened up. The trimming 17 may be in 60

the form of a collar and may be made of any suitable material, such as silk, lace, linen, or the like material. The trim 17 may also fold over the neck portion 28 of the coat. When the lining 15 is used, the trim 17, 18 have the appearance of being part of the coat 10.

To attach the lining 10 to the coat, the slider 30 which remains on one of the slider actuated fastener portions, engages the other complementary fastener portion, and then is moved upwardly on one side of the coat, around the neck line, and then down the other.

It will now be understood that the coat 10 may be worn alone without the lining and may also be worn with the lining 15, depending upon the weather and the suitability for the occasion.

It will now be understood that I have provided a basic garment and a supplementary garment within said basic garment and serving as a lining therefor. The basic garment and the supplementary garment are of substantially the same width and have approximately the same neck configuration and both are open at the front. It will now also be understood that the marginal edges of the supplementary garment extend to the complementary marginal edges of the basic garment, being detachably connected thereto along their front marginal edges and neck portions by complementary fasteners.

For colder weather the lining 15 may be removed and replaced with a lining 40 of a heavier or warmer material, such as wool, or any other suitable lining material. The lining 40 is similar to the lining 15 except that it is provided with a heavy fur collar 41 which folds over the neck portion 28 of the coat 10. The lining 40 is also provided with sleeve portions received within the sleeves 12 of the coat and is attached to the coat by slider actuated fastener means 19 around the edges of the lining below the collar 41 and at the ends of the sleeve portions of the lining. The collar 41 has the appearance of being part of the coat.

It will now be understood that the coat 10 may be worn either alone or with a light lining 15, or with a heavy lining 40. The ensemble is thus suitable for travel or cruise, and eliminates necessity for a number of separate coats or outfits.

In Fig. 9 there is shown a jacket 50 provided with sleeves 51 having linings 52. At the ends of the sleeve linings 12 are slider actuated fastener portions 53. Attached to the sleeve linings 52 are furred cuffs 54 having slider actuated fastener portions 55 united to the fastener portion 53 by usual slider. The jacket 50 may be provided with a collar 56 having a lining 57. Attached to the lining 57 around the edge of the collar is a slider actuated fastener portion 58. The slider actuated portion 58 is made in two symmetrical sections each beginning at the front and terminating in a stop 59 at the back of the neck. The cuffs 54 may be detached from the sleeves and attached to the collar 56 one on each side, the cuff portions 54 together forming a collar for the jacket 50. When the furred cuffs are worn, a coat cannot be worn over the jacket, but when the cuffs are attached to the collar, a coat may be worn over the jacket and the collar (composed of the two cuffs) has the appearance of being a collar for the coat.

The cuffs 54 may also be attached in similar manner to a separate coat 60, as shown in Fig. 13. The wearer may thus have a jacket 50 and a coat 60. When the jacket 50 is worn, the cuffs 54 are worn on the sleeves. When the coat 60 is

worn, the cuffs 54 are attached to the collar and together form a furred collar for the coat 60.

In each instance where slider actuated fasteners are mentioned, it will be understood that the same may be replaced by snap fasteners, buttons, or other quickly detachable fasteners.

Although the collar 41 is illustrated in the drawings as being stitched to the lining 40, it will be understood that the collar may be detachably attached to the lining by snap fasteners, slider actuated fastener means, or any other suitable quickly detachable fastener.

The lining for the jacket of Fig. 9 may also be removably attached to the jacket with the cuffs 54 detachably attached to the lining, either on the sleeves or at the collar.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawings is to be interpreted as illustrative and not in a limiting sense.

Having thus described my invention, I claim as new and desire to secure by Letters Patent:

1. A coat and lining having cooperating fastener means substantially at their neck lines, and a collar carried on the neck of the lining and protruding beyond the neck of the coat and beyond said fastener and being exposed to view.

2. A garment having a pair of collar members forming a complete collar, each member being independently detachably carried by the neck portion of the garment, each of said members when detached forming a cuff member detachably attachable to a sleeve of a garment.

3. A garment having a neck portion, a set of fastener members on each side of the neck portion, and a two part collar, said parts having fastener members, one being complementary to one set of fastener members, and the other being complementary to the other set of fastener members.

4. In combination, a basic garment and a supplementary garment within said basic garment and serving as a lining therefor, said garments being detachably attached together by complementary fastener portions at the front and around the necklines of said garments whereby said garments may be worn together as a single garment, said basic garment being wearable alone independently of said supplementary garment, said supplementary garment having portions extending beyond the fastener portions thereof and protruding from said basic garment and being visible when said garments are worn together, said supplementary garment being a complete garment in itself and wearable as such separately, apart from the basic garment.

5. In combination, a basic garment and a supplementary garment within said basic garment and serving as a lining therefor, said garments being detachably attached together by complementary fastener portions at the front and around the necklines of said garments whereby said garments may be worn together as a single garment, said basic garment being wearable alone independently of said supplementary garment, said supplementary garment having portions extending beyond the fastener portions thereof and protruding from said basic garment and being

- visible when said garments are worn together, said supplementary garment being a complete garment in itself and wearable as such separately apart from the basic garment, said basic garment being collarless and said protruding portion of said supplementary garment being at the neckline thereof and constituting a collar, being folded back over the neckline of said basic garment, and having the appearance of being a collar on said basic garment.
6. In combination, a basic garment and a supplementary garment within said basic garment and serving as a lining therefor, said garments being detachably attached together by complementary fastener portions at the front and around the necklines of said garments whereby said garments may be worn together as a single garment, said basic garment being wearable alone independently of said supplementary garment, said supplementary garment having portions extending beyond the fastener portions thereof and protruding from said basic garment and being visible when said garments are worn together, said supplementary garment being a complete garment in itself and wearable as such separately apart from the basic garment, both of said garments having integral sleeves and means for detachably attaching the ends of said sleeves together.
7. In combination, a basic garment and a supplementary garment within said basic garment and serving as a lining therefor, said garments being detachably attached together by complementary fastener portions at the front and around the necklines of said garments whereby said garments may be worn together as a single garment, said basic garment being wearable alone independently of said supplementary garment, said supplementary garment having portions extending beyond the fastener portions thereof and protruding from said basic garment and being visible when said garments are worn together, said supplementary garment being a complete garment in itself and wearable as such separately apart from the basic garment, both of said garments having integral sleeves, and means for detachably attaching the ends of said sleeves together, the sleeves of said supplementary garment being provided with portions extending beyond the means which attach the ends of the sleeves together, and protruding from the sleeves of the basic garment and being exposed to view.
8. In combination, a basic garment and a supplementary garment within said basic garment and serving as a lining therefor, a line of fasteners on said basic garment substantially at the edge thereof, said supplementary garment having a complementary line of fasteners at its edge except at certain regions where said complementary fasteners are set back a substantial distance from the edge of said supplementary garment, the fasteners on said garments, when engaged causing said supplementary lining to form a protruding and visible portion.
9. In combination, a basic garment and a supplementary garment within said basic garment and serving as a lining therefor, said garments being detachably attached together by complementary fastener portions at the front and around the necklines of said garments whereby said garments may be worn together as a single garment,
- said basic garment being wearable alone independently of said supplementary garment, said supplementary garment having portions extending beyond the fastener portions thereof and protruding from said basic garment and being visible when said garments are worn together, said supplementary garment being a complete garment in itself and wearable as such separately apart from the basic garment, said complementary fasteners being located at the edges of said garments except where the supplementary garment has a portion extending beyond the fasteners thereof.
10. In combination, a coat having back and front portions, a lining therefor detachably attached thereto along the edge portions of the coat, and a collar on said lining protruding from the neck of the coat and being exposed to view when the coat and lining are worn together, said collar being folded back over the neck of the coat, said lining being wearable independently of the coat, and being a garment complete in itself when so worn.
11. In combination, a basic garment and a supplementary garment within said basic garment and serving as a lining therefor, said garments having front and back portions and being detachably attached together by complementary fastener portions arranged along the edge portions of the basic garment and on the inner opposed faces of the basic and supplementary garments and being concealed from view by said garments, whereby said garments may be worn together as a single garment, said basic garment being wearable alone independently of said supplementary garment, said supplementary garment being a complete garment in itself and wearable as such separately apart from the basic garment.
12. In combination, a basic garment and a supplementary garment within said basic garment and serving as a lining therefor, said garments having front and back portions and being detachably attached together by complementary fastener portions arranged along the edge portions of the basic garment and on the inner opposed faces of the basic and supplementary garments and being concealed from view by said garments, whereby said garments may be worn together as a single garment, said basic garment being wearable alone independently of said supplementary garment, said supplementary garment being a complete garment in itself and wearable as such separately apart from the basic garment, superimposed portions of said basic and supplementary garments adjacent attached together edges thereof being foldable back together over the basic garment to expose a portion of the supplementary garment to view when said garments are worn together, without exposing the inner surface of the basic garment.
13. In combination, a basic garment and a supplementary garment within said basic garment and serving as a lining therefor, said garments being of substantially the same width and having approximately the same neck configuration and being open at the front, the marginal edges of the supplementary garment extending to the complementary marginal edges of the basic garment and being detachably connected thereto along their front marginal edges and neck portions by complementary fasteners.
